(57) **CLAIM**

The ornamental design for an elliptical stepper, as shown and described.

DESCRIPTION

FIG. 1 is a bottom, front, and right side perspective view of an elliptical stepper, showing my new design;

FIG. 2 is a top, rear, and left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of a portion labelled 9 in FIG. 1; and,

FIG. 10 is an enlarged view of a portion labelled 10 in FIG. 8.

The broken lines in the drawings depict portions of the elliptical stepper that form no part of the claimed design. The dash dot dash lines in FIG. 1, FIG. 8, FIG. 9 and FIG. 10 are for the purpose of depicting the boundary of the enlarged view and form no part of the claim.
